UNITED STATES PATENT OFFICE.

E. OTTO SCHÜLER, OF FALKENSTEIN, GERMANY, ASSIGNOR TO PERLMANN, SCHAL & STERN, OF NEW YORK, N. Y., A COPARTNERSHIP COMPOSED OF NICHOLAUS PERLMANN, GEORGE SCHAL, AND HERMAN STERN.

DESIGN FOR MACHINE EMBROIDERY.

Application filed September 20, 1922. Serial No. 3,769. Term of patent 3½ years.

To all whom it may concern:

Be it known that I, ERNEST OTTO SCHÜLER, a citizen of the Republic of Germany, residing at Falkenstein i/V, Gartenstr. 67, Falkenstein, Saxony, Germany, have invented a new, original, and ornamental Design for Machine Embroidery, of which the following is a specification, reference be-

ing had to the accompanying drawing, forming part thereof.

The figure is a plan view of an embroidered lace showing my design.

I claim:

The ornamental design for machine embroidery as shown.

ERNST OTTO SCHÜLER.
